(57) **CLAIM**

The ornamental design for a single pod headlamp, as shown and described.

DESCRIPTION

FIG. 1 is a front perspective view of a single pod headlamp suitable for use on a left side of a motor vehicle according to a first embodiment of our new design;

FIG. 2 is a rear perspective view of the single pod headlamp of FIG. 1;

FIG. 3 is a front elevational view of the single pod headlamp of FIG. 1;

FIG. 4 is a rear elevational view of the single pod headlamp of FIG. 1;

FIG. 5 is a top plan view of the single pod headlamp of FIG. 1;

FIG. 6 is a bottom plan view of the single pod headlamp of FIG. 1;

FIG. 7 is a right side elevational view of the single pod headlamp of FIG. 1; and,

FIG. 8 is a left side elevational view of the single pod headlamp of FIG. 1.

FIGS. 1-8 illustrate a first embodiment of our novel design suitable for use on the left side of a vehicle. Our novel design also includes a second embodiment suitable for use on the right side of a vehicle, which is mirrored symmetrical to FIGS. 1-8 and therefore not separately illustrated.

The subject matter shown in broken lines is hereby disclaimed and forms no part of the claimed invention.
